UNITED STATES PATENT OFFICE.

PHILIP DIEHL AND MARTIN HEMLEB, OF ELIZABETH, NEW JERSEY, ASSIGNEES TO THE SINGER MANUFACTURING COMPANY, OF NEW JERSEY.

RUFFLING SEWING-MACHINE.

SPECIFICATION forming part of Letters Patent No. 656,441, dated August 21, 1900.

Application filed June 26, 1899. Serial No. 721,919. (No model.)

To all whom it may concern:

Be it known that we, PHILIP DIEHL and MARTIN HEMLEB, citizens of the United States, residing at Elizabeth, in the county of Union 5 and State of New Jersey, have invented certain new and useful Improvements in Sewing-Machine Rufflers or Gatherers, of which the following is a specification, reference being had therein to the accompanying drawings.

This invention has for its object to provide a sewing-machine ruffling or gathering device which is adapted to be thrown out of action by the attendant while the machine is running, so that the machine may do plain stitching or may form stitched ruffles or gathers, as may be desired, without requiring the rapid operation of the machine to be suspended. Thus in doing such work as sewing sleeves 15 into shirts, where it is desired to gather the fabric during a portion of the seam and to form a portion of the seam plain, the attendant may at any desired moment throw the ruffler or gatherer into or out of operation 20 without stopping the machine, this being preferably effected by a treadle or knee-lever-operated device actuated from beneath the work-plate, thus leaving the hands of the attendant free for the convenient manipulation 25 of the work.

In the accompanying drawings, Figure 1 is a rear side view of one style of Singer sewing-machine with the invention applied thereto. Fig. 2 is a partial plan view of the same. Fig. 3 is a sectional elevation on line 3 3 Fig. 2 looking in the direction of the arrows adjacent to said line. Fig. 4 is a front end elevation of the machine-head with the face-plate removed, and Fig. 5 is a front side elevation of the same. Fig. 6 is a detail view of part of the coupling and uncoupling mechanism.

A denotes the head at the forward end of the machine bracket-arm A'.

B is the needle-bar, operated in a well-known manner from a crank b on the driving-shaft b' through a pitman b².

C is a bracket attached to the head A, and to which bracket is pivoted at c an operating-lever c', connected by a link c² with an elbow-lever c³, carrying the ruffling or plaiting blade

c⁴. The link c² has an adjustable connection at its upper end with the operating-lever c' by means of the curved groove c⁵ in one arm of said lever, the latter being forked at c⁶ at 55 its other end for engagement with a stud d on a vertically-reciprocating operating-bar D, which imparts movement to the said lever c'.

The driving-shaft b' is provided at the rear of the crank b with an eccentric b³, embraced 60 by a forked arm e on a rock-shaft e', having its bearing in a bracket E, attached to the rear side of the head A, said shaft having a second arm e², carrying at its forward end a sliding coupling-pin e³, adapted to engage a 65 notch d' in the operating-bar D.

Loosely mounted on the shaft e' is a lever f, having an incline f', with which the rear end of a small rod f², fitted to slide loosely in the bracket E, is in contact, said rod being pressed 70 toward the incline on said lever by a spring e⁴ on the arm e² of the shaft e'. A spring-lever e⁵, pivotally mounted on the said arm e² and engaging at one end the pin e³, is so placed that its other end is pressed against 75 the forward end of the slide-rod f² by the spring e⁴, so that when the said slide-rod is forced forward or outward by the downward movement of the incline f' of the lever f the coupling-pin e³ will be pressed against the operating-bar D by the spring-lever e⁵, and thus 80 when said pin by the vibration of constantly-moving arm e² comes into register with the notch d' of the said operating-bar said pin will be forced into said notch, thus coupling 85 the said bar with said vibrating arm, and thereby through said operating-bar putting the ruffler or gatherer into action to form ruffles or gathers in the work. The arc of vertical movement of the rear end of the 90 spring-lever e⁵ is so short that said lever does not move out of contact with the outer end of the rod f².

The coupling-lever f is, preferably, actuated by the attendant through a lever f², engaging the forked inner end of the said lever f and connected by a rod f⁴ with a suitable knee-lever or treadle of ordinary construction located beneath the work-plate A² of the machine, thus leaving the hands of the attendant free for the convenient manipulation 100 of the work. The flanges f⁵ at the top and

bottom of the incline f' serve as stops to limit the movement of the lever f by abutting against the upper and lower sides of the slide-rod f^3 .

5 From the foregoing it will be understood that while the rear end of the lever f^2 is held depressed and the coupling-lever f is tilted down, so that the parts are in the positions shown in Fig. 6 and denoted by dotted lines 10 in Fig. 1, the coupling-pin e^3 will be held in engagement with the operating-bar D and the ruffler or gatherer will continue in operation while the machine is running. When it is desired to suspend the operation of the ruffler 15 or gatherer, the attendant releases the knee-lever or treadle, when the pressure of the spring e^4 , acting through the spring-lever e^5 and the slide-rod f^3 , will restore the parts to the positions shown in Fig. 2 and in full lines 20 in Fig. 1, thus uncoupling the pin e^3 from the operating-bar D and throwing the ruffler or gatherer out of action. This coupling and uncoupling of the operating-bar D and its actuating mechanism is easily and instantly 25 effected while the machine is running at any speed and without any appreciable shock or jar, so that gathered or plain sewing at the will of the attendant may be done on high-speed machines without suspending or slackening the running thereof.

We do not claim, broadly, in this application the combination, with a sewing-machine ruffling or plaiting attachment provided with an operating-lever, of a vertically-reciprocating bar in the head of the machine and independent of the needle-bar and connected with and serving to operate said lever, this feature of our invention being claimed in our application No. 721,918, filed simultaneously 35 herewith.

We do not wish to be understood as limiting our invention to the details herein shown, as these may be varied widely without departing from the essence of our invention.

45 Having thus described our invention, we claim and desire to secure by Letters Patent—

1. The combination with a sewing-machine ruffling or gathering attachment, of a bar for 50 operating said attachment, an actuating device for said bar, coupling mechanism for connecting and disconnecting said actuating device and operating-bar, said coupling mechanism comprising a lever having a portion 55 which is inclined relative to the direction of movement of said lever, a sliding rod operated by the inclined portion of said lever, and means for holding said sliding rod in contact with said inclined portion: whereby the attendant may throw the said attachment into 60

or out of operation while the machine is running.

2. The combination with a sewing-machine ruffling or gathering attachment, of a notched, operating-bar for said attachment, independent 65 of the needle mechanism of the machine, a constantly-vibrating arm carrying a sliding coupling-pin adapted to engage the notch of said bar, and a lever controlled by the attendant and provided with a portion which is inclined relative to the line of movement of said lever, which latter is connected with the said coupling-pin to control the movements of said pin in coupling and uncoupling said operating-bar and vibrating arm. 70

3. The combination with a sewing-machine ruffling or gathering attachment, of a notched operating-bar D therefor, a constantly-operating vibrating arm carrying a coupling-pin adapted to engage the notch of said bar, a 80 spring-lever carried by said arm and engaging said pin, a slide-rod to operate said lever, and a movable incline, controlled by the attendant, to actuate said slide-rod and throw the said attachment into or out of operation 85 while the machine is running.

4. The combination with a sewing-machine ruffling or gathering attachment, of an operating-bar therefor, a constantly-moving rock-shaft having a vibrating arm provided with 90 a coupling-pin to engage said bar, a lever provided with an incline, a slide-rod controlled by said incline, connections between said slide-rod and coupling-pin, and means whereby said lever may be actuated by the attendant while the machine is running to cause the said coupling-pin to be engaged with or disengaged from said operating-bar. 95

5. The combination with a sewing-machine ruffling or gathering attachment, of a bar for 100 operating said attachment, an actuating device for said bar, coupling mechanism for connecting and disconnecting said actuating device and operating-bar, said coupling mechanism comprising a lever having an incline, 105 stops for limiting the movement of said lever in either direction, a sliding rod operated by said lever, and means for holding said sliding rod in contact with said incline; whereby the attendant may throw the said attachment into 110 or out of operation while the machine is running, and whereby, also, the movement of the said lever by the attendant, will be limited.

In testimony whereof we affix our signatures in the presence of two witnesses.

PHILIP DIEHL.
MARTIN HEMLEB.
